REVOLVING CAR SEAT

Ernest J. Beck and Clarence A. Van Derveer,
Michigan City, Ind., and King Karpen, Chi-
cago, Ill., assignors to S. Karpen & Bros., a cor-
poration of West Virginia

Application January 8, 1931, Serial No. 507,470

9 Claims. (Cl. 155—96)

This invention relates particularly to a seat adapted for use in railroad coaches and buses, although the invention may be usefully employed elsewhere.

5 The primary object is to provide an improved seat which can be reversed in direction and which, in the operation of reversing the seat, will be laterally shifted. Another object is to provide a seat construction which permits ready rotation 10 of the seat while at the same time preventing chattering or rocking of the seat upon its pivotal connections with the base members. An additional object is to provide improved means for locking the seat-structure upon its base.

15 The invention is illustrated in a preferred embodiment in the accompanying drawings in which—

Figure 1 is a broken rear view of a car-seat constructed in accordance with my invention; Fig. 2 is a side view in elevation; Fig. 3 is a part sectional view, the section being taken as indicated at line 3 of Fig. 2; Fig. 4 is a part sectional view, the section being taken as indicated at line 4 of Fig. 1; Fig. 5 is a plan view, the seat-structure 25 having been removed, and the view being indicated at line 5 of Fig. 1; Fig. 6 is a sectional detail view, the section being taken as indicated at line 6 of Fig. 5; and Fig. 7 is a sectional detail view, the section being taken as indicated at line 7 of Fig. 5.

In the preferred construction shown in the drawings, A designates a base frame which is supported upon standards A'; B designates a carriage or sliding block which is mounted upon the frame 35 A; and C designates a seat plate which is secured to the seat structure D and which is pivotally connected to the carriage or sliding block B; and D designates a seat resting upon seat-plate C.

The base A preferably comprises the end beams 40 1 which rest upon the standards A' and the longitudinal beams 2 which are connected to the end beams 1 to form a rectangular frame. A cross piece 3 connects the side beams 2 at an intermediate point; and a middle beam 4, between the 45 side beams 2, extends from one end of the beam 1 to the cross beam 3. As shown more clearly in Fig. 4, the side beams 2 may be formed in the shape of angle irons so as to provide vertical flanges or sides 5. Secured to the inner edges 50 of the side beams 2 are the retaining strips 6 which are provided with outwardly turned flanges 7 spaced a short distance above the beam 2. Secured to the outer sides of the side beams 2, as shown more clearly in Fig. 5 are bracket walls 55 8 and at an intermediate point within the bracket

walls 8 are bracket supports 9. A cam stud 10 is secured to the middle beam 4 and is preferably provided with a roller 11.

The carriage or sliding block B is preferably rectangular in shape and is provided along its underside with a depending edge or flange portion 12. As shown more clearly in Fig. 4, a strip 13 is secured to the flange portion 12 of the block B and extends under the overhanging lip 7 of the retaining strip 6. By this means, the carriage or block B is slidably secured to the base frame.

As shown more clearly in Figs. 3, 4 and 5, the carriage or block B is provided with a large circular opening and a flange ring 14 at the edge 15 of the opening. Integrally formed with the upper portion of the flange 14 is an inwardly extending flange lip 15.

The seat plate C, as shown more clearly in Figs. 3, 4 and 5, comprises an annular flange portion 16 adapted to rest upon the flange 14 and lip 15 and attached to engage the front face of flange lip 15; lateral arms 17 by which the plate C may be secured to the seat-structure D; and inverted cam casing 18 which is formed within the annular flange portion 16. The cam casing 18 is preferably formed as illustrated in Fig. 5, in the shape of two circles which merge at their point of meeting on one side. The casing 18 is recessed on its underside to form a continuous cam track 19 which resembles the figure 8. The cam track 19 is adapted to receive the cam stud roller 11 which is secured to the middle beam 4 of the base. The inner portions of the cam casing 18 are braced by the web portions 20.

In order to prevent wear along the inner portions of the cam casing 18, we prefer to employ insets 21 of any suitable hard metal and the insets are preferably provided with pointed front ends 22. The inset plugs 21 may be removably secured within the casing 18 by screws 23.

In order to lock the rotatable plate C against rotation, we prefer to employ the following mechanism. A plunger 24 is reciprocally guided in a casing member 25 which is secured to the annular flange portion 16 of plate C. A spring 26, as shown more clearly in Fig. 6 is adapted to urge the plunger in a downward direction. A portion of the annular flange lip 15 of the block or carriage B is cut away at 27, on opposite sides of the 50 block, to receive the plunger 24. The semi-circular recess 27 is shown in Figs. 5 and 6. To accommodate the plunger 24 a similar semi-circular portion 28 is struck from the annular flange portion 16 of the plate C. Rigidly se- 55

cured to the plunger 24 is a pin 29 which extends through a slot 30 in the spring casing 25. The pin 29 extends through a perforation in a pivoted lever 31. The free end of lever 31 extends over the compartment formed by the bracket wall 8 and side wall 12.

In order to actuate the pivoted lever 31, a bar 32 is located in each of the compartments formed by the bracket walls 8 and the side walls 5 and is adapted to raise the outer end of lever 31. Each of the bars 32 is rigidly connected to a shaft 33 which is rotatably mounted in the wall 5 of the base frame. As shown more clearly in Figs. 5 and 7, the treadle member 34 equipped with a bar 35 which is rigidly connected to the shaft 33, is used to rotate the shaft. Bar 35 is normally held in raised position by means of a spring 36 which engages a rear extension 37 of bar 35.

In assembling the plate C with the carriage or sliding block B, the annular flange portion 16 of the seat-plate C is brought into alignment with the annular flange 14 of block B so that the top portion of flange 16 rests upon the flange 14 and the lower portion of flange 16 bears against the front face of the flange lip 15. As shown more clearly in Figs. 3 and 4, a ring track 38 is secured just below the flange lip 15 and ball-bearings 39 are secured between the ring 38 and an annular plate 40. The annular plate 40 is secured by means of bolts 41 to the plate C. If desired, a ring 42 may be interposed between the plate 40 and the seat-plate C. With this arrangement, the plate C and block B may be secured tightly together while the ball bearings 39 interposed therebetween diminish the friction which would otherwise be present.

The operation may be stated briefly:

When it is desired to rotate the seat-structure D, the pedal member 34 may be depressed, thereby rotating a shaft 33 and raising the bars 32. One of the bars 32 engages the free end of the pivoted lever 31 and raises it together with the rigid pin 29 which is secured to the plunger 24. In this way the plunger 24 is withdrawn from engagement with the recess 27 of the sliding block B and the parts are free to be rotated.

As the seat-structure D is turned to effect reversal, the cam stud 10 moving in the cam track 19 causes the plate C and the block B upon which it rests to move laterally upon the base frame. When the plunger 24 reaches the recess 27 on the opposite side of the sliding block, it immediately drops into the recess and locks the parts against further rotation. Meanwhile, the cam 10 has traversed the cam track in one of the two circles. If it is desired to continue the rotation of the seat in the same direction, the treadle member 34 may be operated to release the locking members, as hereinbefore described, and the rotation of the seat may be continued. During this operation, the cam stud passes around the curved track of the other circle and finally reaches the point from which it started. At this point, the plunger 24 drops into the recess within the block member C and the parts are again in their initial position. If desired, the seat-structure may be rotated in either direction and the direction of the rotation changed at any point. The oppositely disposed bars 32 permit the locking members to be disengaged at either side of the seat structure.

The foregoing detailed description has been given for clearness of understanding only and no unnecessary limitations should be understood therefrom, but the appended claims should be

construed as broadly as permissible in view of the prior art.

We claim:

1. In combination, a base, a block slidably mounted thereon, a seat plate equipped with a cam track and connected to said block by an annular connection extending about said cam track, and a cam stud carried by said base member adapted to engage said cam track.

2. In combination, a base member, a carriage slidably mounted thereon, and a plate member provided with an annular bearing connection to said carriage permitting rotation of said plate member, said base member and said plate member being provided with a cam stud and a cam track located within said annular connection.

3. In combination, a base, a block slidably mounted thereon, a seat plate pivotally carried by said block and equipped with a pair of substantially circular cam tracks communicating on one side to form a continuous track, and a cam stud secured to said base and adapted to engage said track.

4. In combination, a base, a carriage slidably mounted on said base, a seat-plate pivotally secured to and carried by said carriage and provided with a continuous cam track resembling in shape the figure 8, and a cam stud secured to the base and adapted to engage said track.

5. In combination, a base, a block slidably mounted thereon and equipped with an annular bearing, a seat plate equipped with an annular bearing rotatively engaging said block bearing, said plate being provided also with a cam track disposed within said bearing, and a cam stud secured to said base and adapted to engage said track.

6. In combination, a base member, a block slidably mounted thereon and equipped with an annular flange bearing, a seat plate equipped with an annular flange bearing rotatively engaging said block flange, said plate being also provided with a cam slot, and a cam stud secured to said base and adapted to engage said slot.

7. A seat comprising, a base, a block slidably mounted thereon, a seat-plate pivotally secured to said block, said seat-plate being provided with a pair of substantially annular cam tracks communicating on one side, removable hard metal bearing inserts secured in said tracks adjacent the points of communication between said annular track portions, and a cam stud carried by said base adapted to engage said tracks.

8. A seat comprising, a base, a block slidably secured to said base, a seat-plate pivotally secured to and carried by said block, said plate being provided with a curved cam track, a cam stud carried by said base and adapted to engage said track, and releasable locking means adapted to secure said seat-plate to said block.

9. A seat comprising, a base, a block slidably secured to said base, a seat plate pivotally secured to and carried by said block, said plate being provided with a curved cam track, a cam stud carried by said base and adapted to engage said track, releasable locking means adapted to secure said seat-plate to said block, said means comprising a spring pressed plunger adapted to engage recesses in said plate and block, and treadle-actuated levers adapted to raise said plunger.
